UNITED STATES PATENT OFFICE

2,583,038

GUM MASSAGER AND TOOTH CLEANER

Robert A. Birch, Greenwich, Conn.

Application June 26, 1950, Serial No. 170,428

4 Claims. (Cl. 128—62)

1

The present invention relates to a gum massage device.

It is a well known fact, that the gums of human beings recede due to lack of proper blood circulation. Receding gums cause the teeth to become loose, and in time the teeth have to be extracted. It has been found that by massaging the gums with the fingers, the gums retain their color, and to some degree remain firm. Although the fingers help to prevent the gums from receding, it is not altogether satisfactory for the reason it is difficult to massage the inner gums.

It is an object of the present invention to provide a gum massage device that will effectively massage the upper and lower gums both inside and outside.

Another object of the present invention is the provision of means associated with the device that will gently engage the gums and uniformly massage them.

A still further object of the present invention is the provision of soft rubber pads having means for engaging the gums at the teeth line.

A still further object of the present invention is the provision of soft rubber pads having a plurality of various size gum massaging means.

A still further object of the present invention is the provision of soft rubber pads that are detachable and easily cleaned.

A still further object of the present invention is the provision of means upon which the soft rubber pads are mounted.

A still further object of the present invention is the provision of means for moving one of said means upon which one of the soft rubber pads is mounted toward and away from the other means upon which one of the soft rubber pads is mounted.

A still further object of the present invention is the provision of means shaped to the contour of a human mouth and means for moving one of the said shaped means.

A still further object of the present invention is the provision of a massaging device having resilient spring means.

Like reference numerals indicate like parts in all of the views.

Other and further objects and advantages of the invention will be apparent from the following description when taken in connection with the accompanying drawing, wherein:

Figure 1 is a side elevational view of the massage device without the soft rubber pads.

Figure 2 is a top view of Figure 1.

2

Figure 3 is a view taken on line 3—3 of Figure 1 looking in the direction of the arrows.

Figure 4 is an elevational view of one of the soft rubber pads showing the arrangement of the gum engaging means.

Figure 5 is a sectional view taken on line 5—5 of Figure 4.

Figure 6 is a fragmentary vertical view of another soft rubber pad.

Figure 7 is a sectional view taken on line 7—7 of Figure 6.

Figure 8 is a perspective view of another modified form of the invention.

Figure 9 is a perspective view of another modified form of the invention.

Referring to the drawings, the numeral 15 represents the gum massage device comprising a pair of handles 16 and 17, handle 16 having a reduced front end 18 with transverse bore and a depending pin 19. Handle 17 is provided with an angular portion 20, slot 21 in the angular portion, a tubular portion 22, one end of which is integral with a band 23 that is of a substantially U-shape configuration, the band tapering toward the ends, the ends 24 being rounded. The reduced end 18 is pivotally connected in the slot 21 by a rivet 25.

A slide bar 26 is mounted in the tubular portion 22, one end of the plate carrying a substantially U-shaped band 27, the top edge 28 of which is horizontal, the ends 29 being rounded, the bottom edge 30 being curved. The end of the slide bar 26 is provided with an aperture that receives the pin 19. The bands 23 and 27 are held in spaced inoperative position by a spring 31 that is carried by the handle 17, the end 32 of the spring impinging the top face of the handle 16. As shown in Figures 1 and 2, the bands 23 and 27 are held in spaced relation by spring 31, these views representing the inoperative position of the device.

The rubber pad shown in Figure 4 is adapted for engagement with and disengagement from the band 23, and it comprises a body 33 of resilient rubber, having rolled edges and a flat back wall 35, the inner wall of the rolled edges being in spaced relation to the flat back wall 35 providing a channel 36 for engagement with the band 23 and securely holding the pad on the band 23. The outer face 37 of the pad tapers from its rolled edges outwardly toward its mid-way point, the body being thicker at this point as shown in cross-section in Figure 5, then at any other point. The outer face 37 is provided with a plurality of knobs 38 that are adjacent the rolled edges, and

a plurality of smaller knobs 39. Adjacent the horizontal center line of the outer face, and on each side thereof, there are provided ridges 40 that are of substantially V-shape configuration, and these ridges are so positioned that they will be in alignment with and engage the outer upper and lower gum line 41, of the gums. Between the ridges 40 there is provided a plurality of conical shaped studs 42 that are adapted to engage the teeth 55 and serve as a cleaning medium. Midway the ends of the body 33 and the rolled edges 34 there is provided a slot 44 that allows the slide bar 26 to move back and forth freely so that there is no binding of the plate with the pad.

The rubber pad shown fragmentarily in Figure 6 is adapted for engagement with and disengagement from the band 27, and it comprises a body 45 also of resilient rubber and having rolled edges 46, and a flat back wall 47, the rolled edges being in spaced relation to the flat back wall, providing a channel 48 for engagement with the band 27, the body being tapered to fit the contour of the band 27. The outer face 49 of the pad tapers from its rolled edges outwardly toward its midway point, the body being thicker at this point as shown in the cross-sectional view Figure 7, and it is to be noted that in this view the pad is mounted on the band 27. The outer face 49 is provided with a plurality of knobs 50 that are adjacent the rolled edges, and a plurality of smaller knobs 51. Adjacent the horizontal center line of the outer face, and on each side thereof, there are provided ridges 52 that are of substantially V-shape configuration, and these ridges are so positioned that they will be in alignment with and engage the inner gum lines 53 of the upper and lower gums. Between the ridges 52 there is provided a plurality of conical shaped studs 54 that are adapted to engage the teeth 55 and serve as a cleansing medium. Midway the ridges 52 and the ends of the body 45 there is an element 56 extending from the outer surface or face 49 to prevent the teeth from contacting slide bar 26. The body 49 and the element 56 are provided with a slot 57 that is engaged by the slide bar 26.

In the modified form of the invention shown in Figure 8 the handles 95, 96, tubular portion 97, slide bar 98, pin 99 and spring 100 are similar to the elements shown in Figure 1 of the drawings, the handles being in reversed position. The tubular portion 97 on one end is provided with a band 101 upon which is mounted a resilient massage pad 102 having a concave area 104 mid-way the top and bottom edges, the bottom edge 105 and top edge 106 being semi-circular. The slide bar 98 is provided on one end with a three quarter circular band 107 upon which is mounted a resilient massage pad 108 having a concave area 109 mid-way the top and bottom edges, the bottom edge 110 and the top edge 111 being rolled or semi-circular, and due to the configuration of these pads a simulated action similar to using thumb and forefinger on the gums will be obtained.

In the modified form of the invention illustrated in Figure 9, the handles 115, 116, tubular portion 117, plate 118, pin 119 and spring 120 are similar to the showing in Figure 13. The tubular portion 117 is provided with a transverse slot 121 in which are mounted two transverse arms 122, each of the arms being provided with a slot 123 that is disposed at an angle, the arms being retained in the tubular portion 117 and

connected to plate 118 by a rivet 124. The outer ends of the transverse arms are provided with apertures 125 that receive shafts 126, upon which are mounted resilient massage elements 127. In this form of the invention when the handles 115, 116 are moved the plate 118 is moved and the arms 122 due to the slots 123 are moved back and forth, the gums being contacted by the massage elements 127.

10 In the use of the device shown in Figure 1, the pad 33 is affixed to band 23 and pad 45 affixed to band 27. The device is then ready to be inserted into the mouth of a person, the elements on pad 23 facing the outer wall of the upper and 15 lower gums, the elements on pad 27 facing the inner wall of the upper and lower gums. The handles 16 and 17 are held in one hand, handle 16 being pivotally connected to handle 17 moves when a squeeze is put on the handles, and during 20 the squeeze, handle 16 moves toward handle 17 against the pressure of spring 31, and during this movement slide bar 26 is moved inwardly due to pin 19 drawing the band 23, massage elements on pad 33 into engagement with the inner gum walls, 25 while the massage elements on pad 45 engage the outer gum walls. Constant manipulation of the handle 16 causes a light impingement of the massage elements on the pads 33 and 45 to the walls of the gums, gently massaging them, the massaging causing blood to circulate in the gums, handle 16 being responsive to spring 31. After the gums have been massaged and the teeth cleaned, the pin 25 is removed, releasing handle 16, the pin 19 30 disengaged from slide bar 26, the band 27 with pad 45 and plate 26 removed from the tubular portion 22, and pads 33 and 45 removed from the respective bands and washed.

In the operation of the device shown in Figure 8, the configuration of the pads is such that the 35 gums will be massaged in a more effective way than a person could by merely using thumb or forefinger.

In Figure 9 the massage is accomplished by 40 placing the resilient balls 127 against the gum, then squeezing the handles, and the massage elements 127 will rotate due to the mounting of the shaft as the handles are moved transversely by the hand.

45 From the foregoing description, when taken in connection with the accompanying drawings, the advantages of the construction and operation will be apparent to those skilled in the art to which the invention appertains, and I desire to have it understood that the device shown is merely illustrative and that such changes may be made within the scope of the claims hereto appended.

50 What is claimed is:

1. A dental device for massaging teeth and 55 gums comprising a fixed member, a movable member mounted on said fixed member and being linearly slidable with respect thereto, a resilient pad on said fixed member, a resilient pad on said movable member, and means connected to said movable member for reciprocating said movable member with respect to said fixed member whereby said resilient pads are reciprocated with respect to each other.

2. A dental device for massaging teeth and 60 gums comprising a fixed member, a movable member mounted centrally in said fixed member and being linearly slidable with respect thereto, a resilient pad on said fixed member, a resilient pad on said movable member, and means connected to said movable member for reciprocating

said movable member with respect to said fixed member whereby said resilient pads are reciprocated with respect to each other.

3. A dental instrument for simultaneously cleaning and massaging the upper and lower gums and teeth, comprising a fixed handle, a movable handle, said movable handle being pivotally connected to said fixed handle, a channeled portion on said fixed handle, a member slideable in said channeled portion and connected to said movable handle whereby movement of said movable handle will slide the slideable member in the channeled portion, and means on said fixed handle and on said slideable member for massaging and cleaning the gums and teeth.

4. A dental instrument comprising a fixed handle, a movable handle pivotally connected to said fixed handle, a channeled portion on said fixed handle, a plate carried by said fixed handle, a resilient pad on said plate, a member slideably mounted in said channeled portion and hav-

ing one end connected to said movable handle whereby movement of said movable handle will slide the slideable member in the channeled portion, and a plate on said slideable member and carrying a resilient pad, said resilient pads being adapted to massage the gums and teeth.
